PUMP

Zbigniew C. Dobrowolski, Boston, Mass., assignor to The New York Air Brake Company, a corporation of New Jersey

Filed Apr. 3, 1963, Ser. No. 270,211
1 Claim. (Cl. 230—158)

This invention relates to vacuum pumps of the rotary piston type. Particularly, the invention relates to the balancing of a triplex rotary piston pump.

As known in the art, a rotary piston pump includes a housing having a circular right cylindrical pumping chamber therein. A shaft is journaled in suitable bearings carried by the housing and extends coaxially through the pumping chamber. A circular cam is eccentrically mounted on the shaft in the pumping chamber. A strap encircles the cam. A valve piston extends radially outward from the strap and passes through a guideway formed in an oscillatory pin journaled in the housing. The valve piston is hollow and has an opening through one side face near the strap. This provides an inlet to the pumping chamber. An outlet connection extends through the housing from the pumping chamber. The inner end of the outlet connection is located near the valve piston on the side opposite the lateral opening therein.

In the past, both simplex and duplex rotary piston pumps have been manufactured. The rotary speeds of such pumps have been limited by the characteristic imbalance of such pumps. According to the prior art, attempts have been made to improve the balance of such pumps by the use of counterweights mounted for rotation with the shaft and careful correlation of the weights of the cams and the counterweights and their positions. Such balancing schemes have not proven satisfactory because the resulting bearing reaction forces were unbalanced causing large shaft deflections unless a large diameter shaft is used. Such schemes also overlook the mass and the true nature of the motion of the valve pins and straps, the problem being treated as one of rotary unbalance. Also ignored are gravity forces and the unbalanced pressure forces on opposite sides of the valve piston and strap assembly.

Because of the unsatisfactory nature of known balancing methods, it has been necessary to make large increases in pump size to achieve commensurate increases in pumping speed.

Applicant has made it possible by practice of his novel balancing scheme to increase rotary speed twofold in all rotary piston pumps except small sized units in which the rotary speed is increased threefold.

According to applicant's teaching, the pump is constructed as a triplex unit. Three pumping units, each comprising a cam, a strap, a valve piston and a guide pin, are mounted in axially spaced relation on a single shaft. The mass of the cam, strap and valve piston, respectively, of each end unit is equal to half the mass of the corresponding parts of the intermediate pump unit. The distribution of mass of the cam, strap, and valve piston, respectively, of each unit is the same as that of the same parts in all other units. The center of mass of the moving parts of each pump unit is located on a transverse median plane passing through that unit normal to the shaft. The centers of mass of the cams, and valve pistons, respectively, of one end unit are longitudinally aligned with the centers of mass of the corresponding parts of the other end unit and angularly displaced 180° from the centers of mass of the corresponding parts of the intermediate pump unit. Preferably, but not necessarily, the guide pins of all three units are substantially aligned. Even if the pins are not aligned, all must lie on a single plane passing through the shaft

2

axis. The masses of the guide pins of the end units are equal and each has a mass one half that of the pin of the intermediate unit.

The intermediate unit is preferably a single unit, but it may comprise two units, each identical to the end units. The cams may be hollow or solid. The hollow cam is preferred because the pump can start up without excessive power consumption. The damping effect achieved through use of solid cams will give better damping of upper harmonics of the vibration and they may be used for that reason.

The preferred embodiment of the pump will be described having reference to the accompanying drawing in which:

FIG. 1 is a sectional view on line 1—1 of FIG. 2.

FIG. 2 is a sectional view on line 2—2 of FIG. 1.

FIG. 3 is a diagrammatic view showing the phase relationship of the cams.

The pump includes a housing 11, which includes a main body portion 12 having a transverse partition 13 formed integrally therewith, a removable partition 14 mounted therein and end covers 15 and 16 mounted therein. The partitions and end covers define between them pumping units 17, 18, and 19. All three pumping units 17, 18, and 19 are mounted on a single shaft 21 journaled in suitable bearings in the end covers 15 and 16 and in the transverse partitions 13 and 14. The pumping units 17, 18 and 19 include the same parts, though unit 18 has substantially twice the axial length of unit 17 (or 19). Pumping unit 19 is shown in detail in FIG. 1. It includes a right circular cylindrical pumping chamber 22 coaxial with shaft 21. A circular cam 23 is mounted eccentrically on shaft 21. An annular strap 24 encircles the cam and has its inner surface mounted with a good running fit on cam 23. The diameter of the cam is chosen so that at the point of maximum eccentricity the outer periphery of the strap is closely fitted to the inner surface of the pumping chamber 22. A valve piston 25 projects upward from the strap 24 and is guided in a guideway formed in cylindrical guide pin 26. The guide pin 26 is journaled in bearing recesses formed in end wall 16 and partition 14 (see FIG. 2). The valve piston 25 has a cored opening 27 extending into it from its upper end. An opening 28 is formed in the side wall of the valve piston near the strap 24. The suction connection is shown at 29 and the discharge connection appears at 31. A spring biased valve 32 prevents back flow through the discharge connection. A water jacket 33 is formed in the housing and has inlet and outlet connections 34 and 35.

The same parts of pumping units 17 and 18 are indicated in FIG. 2 by the same reference numerals used in describing pumping unit 19 except that respectively 100 and 200 have been added to these reference numerals.

Referring now to FIG. 3, it will be seen that cams 23 and 123 are mounted in phase with each other, i.e., the directions of eccentricity are the same, whereas cam 223 is mounted 180° out of phase with cams 23 and 123, i.e., the direction of eccentricity of cam 223 is opposite to that of cams 23 and 123. Thus, as shown in FIG. 2, pumping units 17 and 19 are at top dead center position, whereas pumping unit 18 is at bottom dead center.

In FIG. 2, the space or system to be evacuated is shown schematically and identified by reference numeral 36. As shown, this space 36 may be connected in parallel with the suction connections 29, 129 and 229 of the pumping units 17, 18 and 19 or the pump may be operated as a multi-stage pump with the units 17 and 18 connected in parallel flow relation between the space 36 and the inlet 29 of the unit 19. The size relationship of the units gives a desirable staging ratio of 3:1, whereby the first stage units 17 and 18 and the second stage unit 19 have substantially equal mass rates of flow, i.e., pumping speeds

though the volume of the pumping chambers in the lower and upper stages differ in a ratio of 3:1.

The cam 123 has a mass equal to that of cam 23. Both cams are hollow and the mass of each is identically distributed. The cam 223 has a mass twice that of cams 23 and 123. Also, it is substantially twice as long as cams 23 and 123, and has substantially the same diameter. Actually, in the illustrated preferred embodiment, cam 223 is slightly smaller in diameter and slightly more than twice as long as cam 23 or 123. Pumping chamber 222 is similarly proportioned. This difference in the diameters of the pumping chambers 22 and 222 provides a shoulder by which removable partition 14 may be precisely positioned normal to shaft 21. In order to distribute the mass of cam 223 in the same way as the masses of cams 23 and 123 are distributed, the end walls and the central axial web of cam 223 are twice as thick as those of the end walls and webs of cams 23 and 123. The cylindrical peripheral walls of all three cams are substantially equal in thickness.

The centers of mass of cams 23, 123 and 223 lie on a single plane passing through the shaft axis, the center of mass of cam 223 lying on the opposite side of the shaft from those of cams 23 and 123. This plane also passes through the geometric centers of the cams which are similarly arranged. The hollow cams are so designed that the center of mass and geometric center of each cam are approximately coincident.

The guide pins 26, 126, and 226 are shown axially aligned with one another. With this arrangement, the pumping action of the end units is 180° out of phase with that of the intermediate unit. The pin 226 and the valve piston 225 of the intermediate unit can lie on the opposite side of the pumping chamber 222 from the pins 26 and 126 and valve pistons 25 and 125. In other words, the pins 26 and 126 are aligned and lie in a common plane passing the axis of the pump with pin 226. When the valve piston and pin of the center unit 18 are displaced in this manner, the units will pump in phase with one another even though the phase relation between the cams is unchanged.

The triplex pump of the present invention can be operated at rotary speeds of over 900 r.p.m. This contrasts favorably with maximum rotary speeds of 360 r.p.m. and 450 r.p.m. achieved respectively in commercially available simplex and duplex rotary vacuum pumps. In small sizes, such as 5 c.f.m., duplex pumps have been operated at speeds up to 600 r.p.m. A pump constructed in accordance with the present invention and having a volumetric displacement equal to that of the 5 c.f.m. duplex pump can be operated at speeds up to 1800 r.p.m. and a pumping speed of 15 c.f.m. is achieved.

The balance of the pumps built in accordance with this invention is so good that it is not necessary to bolt their supporting mounts as was the case with the prior simplex and duplex pumps.

The invention is not limited to use with the structure of the illustrated pump, and no such limitation should be

inferred except as expressly recited in the appended claim:

What I claim is:

A vacuum pump comprising:

- (a) shaft means;
- (b) three pumping units spaced along the shaft means and driven thereby, the end units operating in phase with one another and 180° out of phase with the intermediate unit;
- (c) each pumping unit consisting of a rotary piston pump and including:
  - (1) a housing having a close-ended right circular cylindrical pumping chamber therein concentric with said shaft means,
  - (2) a right circular cylindrical cam eccentrically mounted on the shaft means in said chamber,
  - (3) a strap journaled on the cam and having a right circular cylindrical outer peripheral surface, and having its element of maximum eccentricity in sealing contact with the cylindrical wall of the pumping chamber,
  - (4) a rotary pin, whose axis is parallel with the axis of the shaft means, journaled in the housing adjacent the pumping chamber and having a transverse guideway extending therethrough, and
  - (5) a valve piston projecting outward from the strap through said guideway;
- (d) in which the mass of the cam, strap, and piston, respectively, of one end unit is equal to the mass of the same parts in the other end unit and equal to one-half the mass of the corresponding parts of the intermediate unit;
- (e) in which the cam, strap, and valve piston of one unit have a mass distribution about the axis of the cam, which is the same as the mass distribution of the corresponding parts of the other units about the corresponding axis; and
- (f) in which the center of mass of the cam and strap of the intermediate pump unit are oppositely displaced from the axis of the shaft means with respect to the displacement of the centers of mass of the cams and straps of the end pump units;
- (g) in which the axis of the pins of both end pump units and of the intermediate pump unit lie in a plane passing through the axis of the shaft; and
- (h) the centers of mass of each pump unit lie on a median plane of the pump unit normal to the axis of the shaft.
